J. F. BATES

CARBURETOR

Filed August 18, 1923

UNITED STATES PATENT OFFICE.

JAMES FRENTRICK BATES, OF BELMONT, WELLINGTON, NEW ZEALAND.

CARBURETOR.

Application filed August 18, 1923, Serial No. 658,085, and in New Zealand September 8, 1922.

My invention relates to carburetors, and particularly for that type where the carburetor is inserted into the main fuel tank or chamber containing the hydrocarbon fuel, and in which the air is drawn through the fuel to charge it with the explosive vapour.

According to my present invention the carburetor consists of a telescopic pipe depending into the tank, the lower end of such pipe containing a float, and orifices or perforations through which the air is drawn.

In one form of the carburetor the air induction pipe depends through a cap or cover for an opening in the tank large enough for the insertion of the float upon the lower end. This induction pipe depends downwardly a desired distance to form a section and upon such section another section slides having a stop whereby it will not pass the end of the first section. Upon this second section a third pipe slides also having a stop so that it will not pass beyond the end of the second section. The lower end of this third section is provided with orifices or perforations for the passage of air to the fuel. Near the lower end of this third section a float is arranged whereby the orifices are retained the desired distance below the level of the surface of the fuel. The float and section may be guided by means of rods depending from the cap and such rods may pass through holes in the float if desired. The intake pipe to the engine may lead from the cap or from any other part of the tank.

In another form, the air induction pipe may depend to near the bottom of the fuel tank and upon this pipe a section slides containing stops or rings upon its lower end, while a second section slides over this first section, the downward movement being limited by the stops referred to. The second section has a ring whereby it is guided upon the induction pipe, while upon the second section a third section slides also having stops to limit its downward movement. The end of this section is closed and slides upon the induction pipe and has orifices or perforations for the passage of air, the float being attached immediately above the orifices.

Any number of telescoping sections may be employed provided they are guided and have means to prevent air passing between them.

The invention will now be described with

reference to the accompanying drawing, wherein:

Figure 1, is a sectional elevation of the carburetor collapsed.

Figure 2, is a section through a fuel tank showing the carburetor depending to the bottom of the tank.

Figure 3, is a view of an enlarged detail.

Figure 4, is a sectional view of a modified form.

Figure 5, is a view of an enlarged detail.

Figure 6, is an enlarged sectional plan through the carburetor shown in Fig. 4.

According to Figures 1 to 3, the air induction pipe 1 passes through a cap 2 screwed upon a neck 15 of the tank 9. This induction pipe is screwed upon a tubular section 3 which depends downwardly into the tank a desired distance, and upon such section another section 4 slides. The section 3 has a flange 5 at its lower end upon the exterior thereof, while the section 4 has a similar flange 6 at its top end upon the inside thereof (Fig. 3). Because of the flanges 5 and 6 the section 4 can not pass the lower end of the section 3. Two other telescopic sections 7 and 8 have similar cooperating stops whereby they are enabled to be extended to the bottom of the tank 9. Upon the lower end of section 8 a float 10 is placed, while the lower end of such section is provided with orifices 11. The float 10 and sections are guided vertically by means of rods 12 passing through holes in the float. These rods are fixed to a plate 13 supported upon a circumferential shoulder 14 of the neck 15 of the tank. The plate 13 is provided with orifices 16 for the passage of the mixture which passes to the engine through the induction pipe 17.

In operation, the air is drawn by the suction of the engine into the pipe 1, thence into the sections 3 to 8 where it passes through the perforations in the bottom of the section 8, thence through the upper surface of the fuel and through the perforations 16 and into the pipe 17 which leads to the engine.

In the modification illustrated in Figure 4, the air induction pipe 1 depends to near the bottom of the fuel tank and upon this pipe the tubular sections 20, 21 and 22 are adapted to slide. The sections 20 and 21 have rings 23 at their bottom ends (Fig. 5) whereby they are slidably guided upon the

pipe 1 and to provide an annular space 24 between the wall of the sections and the pipe. The upper end of the section 20 has a flange 25 to slide upon the air induction pipe, and the section is limited in its downward travel by means of the flange 25 engaging a ring 26 upon the pipe. The rings 28 upon the bottom ends of the sections 20 and 21 are provided with a number of perforations 27 (Fig. 5) so that there is communication between the annular spaces. The section 21 slides upon the section 20 and the section 22 slides upon the section 21. The bottom ends of the sections 20 and 21 have outwardly projecting flanges 28 which support the sections 21 and 22 by means of inwardly formed flanges 29 upon the top ends of such sections.

The induction pipe 1 is formed with ori-
fices 30 at a position near the upper part of
the section 20, while the section 22 may have
a spherical or otherwise shaped bottom
which is provided with a number of perfora-
tions 31 through which the air passes. A
float preferably of circular form is attached
to the lower end of the bottom section 22
above the perforations 31. This float should
be of a buoyancy sufficient to sink the perfora-
tions 31 just below the surface of the fuel
and may be adjustable upon the bottom sec-
tion by any suitable means. Air will be
drawn through the induction pipe entering
through the holes 30 into the interior of
the sections, as indicated by the arrows in
Figure 5. The air then passes through the
perforations 27 and through the perfora-
tions 31 in the bottom section and becomes
charged with fuel. More or less than three
sections may be used according to the depth
of the fuel tank. The neck 33 is such that
the section of largest diameter of the floating
distributor may be passed through it and
also allow sufficient area for the gaseous
mixture to pass through the pipe into the
engine, even when the floating distributor is
at its highest position within the neck. The
depth of the neck is such that when the sec-
tions are at their highest positions within

the neck they will not extend beyond the
depth of the neck so that the tank can be
filled to its maximum capacity. The top of
the neck is closed by a cap 34 while the air
induction pipe 1 is fixed to this cap and so
also the connection 35 for attachment to the
pipe leading to the engine. The air induc-
tion pipe may be provided with a number of
perforations 36 one being shown in Fig. 4
which perforations extend partly around the
pipe at a position directly beneath the opening
in the induction to the engine and form
auxiliary air inlets.

The tank is preferably made as shown in
Figure 2, and is of the usual circular form,
but provided with slightly sloping false
bottoms 37 so as to leave a well 38 at the
bottom of the tank into which the lower end
of the bottom section depends so that all
the fuel may be used.

I claim as my invention:

1. In a carburetor, the combination of a
fuel tank, an induction pipe depending into
said fuel tank, a plurality of telescopic sec-
tions supported from said induction pipe
and slidable with respect thereto and adapt-
ed to move to the bottom of the said tank,
a float mounted upon the bottom section, the
said sections having flanges at their ends to
support the lower sections from the upper
and to limit the shifting of said sections rela-
tive to each other.

2. A carburetor, comprising a fuel tank
provided with a neck, a plate supported by
said neck, rods depending from said plate,
an air induction pipe extending into said
fuel tank through said plate, a plurality of
telescopic sections supported from the said
air induction pipe and slidable with respect
thereto, and adapted to move to the bottom
of said tank, a float mounted on the bottom
section, and means for supporting the said
sections from each other, the said float and
the said sections being guided by the said
rods.

In testimony whereof, I have signed my
name to this specification.

JAMES FRENICK BATES.
